UNITED STATES PATENT OFFICE.

IRA B. HUBBARD AND CHESTER E. WILLIAMS, OF WORCESTER, MASSACHUSETTS.

COMB-HEAD.

1,165,177.

Specification of Letters Patent. Patented Dec. 21, 1915.

Application filed January 2, 1914. Serial No. 809,879.

To all whom it may concern:

Be it known that we, IRA B. HUBBARD and CHESTER E. WILLIAMS, citizens of the United States, both residing at Worcester, in the county of Worcester and State of Massachusetts, have invented a new and useful Comb-Head, of which the following is a specification.

This invention relates to a head for doffer combs and the principal objects thereof are to provide simple and inexpensive improvements in the mechanism for connecting the crank spindle with the comb shaft whereby the same can be very materially speeded up; to provide a construction of these parts that will permit of the use of ball bearings for the purpose of permitting the increase of speed and to get all the ball bearing parts in one piece; and to so arrange the parts that they can be made of steel and will have no angles or projections that will render them easily breakable in ordinary practice.

Further objects and advantages of the invention will appear hereinafter.

Reference is to be had to the accompanying drawings in which—

Figure 1 is a plan of the bottom half of a comb head with the parts constructed in accordance with this invention and certain of said parts shown in section on the plane of the top of the comb head casting; Fig. 2 is a sectional view of the same on the line 2—2 of Fig. 1; Fig. 3 is a similar view with the arm stud also in section; Fig. 4 is a central longitudinal sectional view of the link with its parts separated therefrom and shown partly in elevation; and Fig. 5 is an elevation of the driving shaft.

The invention is shown as applied to a doffer comb head comprising a main casting 10, a crank spindle or driving shaft 11 driven by a pulley 12 thereon, and a comb shaft 13 connected with a vibrating shaft 14.

As ordinarily constructed the shafts 11 and 14 are connected by two members, a link eccentrically connected with the shaft 11 and an arm fixed to the shaft 14 are pivoted to the link. These two parts have been made heretofore each with a projection at each end transverse to the main body of the link or arm.

The arm has always been made as a casting and the link has in recent years been made of steel. It has not been practical to make the arm of steel, and consequently, it will be seen that this arm has necessarily

been made quite heavy in order to provide a structure strong enough to withstand the very high rate of vibration. It has been made larger than would have been necessary if it did not have the two hollow projections at its ends connected by a comparatively thin but wide body. This shape introduced weaknesses at the angles between the body and the projections and these weaknesses had to be compensated for by making the device comparatively large. It has been found in practice that this part breaks frequently and not only necessitates expense for repairs but necessitates the stopping of the machine for considerable periods of time. The steel link also occasionally breaks with similar results. According to this invention ball bearings are arranged in these parts in such a way that the ball bearings will all be located on one part, which in itself can be made of a flat piece of steel without the projections referred to and the other one of these two pieces can also be simplified to such an extent that it can be made of steel. In this way we find that the speed can be very materially increased thus adding a very high percentage to the amount of production and yet the changes made are in the direction of simplicity, and breakage is reduced. Moreover generally if anything breaks it is a comparatively simple part that is easily and quickly replaced.

Referring now to the drawings again it will be seen that the crank spindle 11 is provided on the end with an eccentric projecting crank 15. The link 16 which takes the place of the old link is a flat member having no material projections and easily made of steel. This member is provided with two recesses 17 therein each one adapted to receive a ball retainer 18 which fits up against a ridge 19 on one side of the link. The ball retainers are held in position by a plate 20 which is screwed or otherwise fixed to the link, and has opposite pairs of arms partly encircling the ball retainers and holding them in position. The crank stud 15 enters one of the ball retainers and the other one receives a stud 22 which is fixed in a steel arm 23 which is fixed to the shaft 14 by a screw 24 or in any other desired way. The provision, however, of the steel link 16 with the ball bearings arranged therein in the simple manner set forth results in a great reduction in the amount of wear and permits of a much simpler arrangement for the arm

23 and it has been found in practice that the speed can be increased several hundred vibrations per minute and the durability is greater than before even under these increased duties.

Although we have illustrated and described a specific embodiment of the invention, we are aware of the fact that many modifications can be made therein by any 10 one skilled in the art without departing from the scope of the invention as expressed in the claims, therefore, we do not wish to be limited to all the details of construction herein shown and described, but

15 15. What we do claim is:—

1. In a device for operating doffer combs, the combination with a crank spindle and a comb shaft parallel therewith, of a projecting eccentric crank pin on the end of said 20 crank spindle, a flat link having no projecting parts but provided with two openings therethrough at opposite ends, a bearing in one opening for receiving said crank pin and a second bearing in the other opening, a 25 steel arm fixed with respect to the comb shaft, and a stud mounted on said arm and passing into the second bearing.

2. In a device for operating a vibrating

comb, the combination of a flat link having no projecting parts but provided with two 30 openings therefrom at opposite ends, a bearing in one opening for securing a crank pin, a second bearing in said opening, a steel arm and a stud mounted on said arm and passing into the second bearing.

3. In a device for operating an oscillating comb, the combination with a crank spindle, and a shaft, of a link for transmitting the rotation of the spindle and the shaft as a vibration, said link consisting of a flat piece 40 of steel having recesses therein at its opposite ends, a ball retainer in each recess, a plate secured to the link between said recesses and having arms projecting oppositely over the edges of said ball retainers and 45 projections on said spindles and shafts entering said ball retainers.

In testimony whereof we have hereunto set our hands, in the presence of two subscribing witnesses.

IRA B. HUBBARD.
CHESTER E. WILLIAMS.
